Des. 435

William Savery, of New York, N.Y.
Letters Patent No 435. Dated Jan'y 6. 1852.

The schedule referred to in these Letters Patent and
making part of the same.

To all whom it may concern:

Be it known, that I, William Savery, of the city, county & state of New York, have invented a new & useful design for stove plates to be moulded in sand, and cast in iron: and I do hereby declare that the following is a full and accurate description of the same, reference being had to the accompanying drawings:

A. No. 1 represents the Front Plate.

B. No. 2 represents the Bottom Plate.

C, C, openings or holes in Bottom Plate.

What I claim as new & original, and wish to secure by letters patent is the design & configuration of the several ornamental figures on the Front & Bottom plates of a certain stove as represented in the annexed drawings, & as above described.

Witnesses,

Alexander Lam 3
E. G. Van Schaack 3
